(57) **CLAIM**

The ornamental design for a bottle, as shown and described.

DESCRIPTION

FIG. 1 is a front perspective view of a bottle incorporating our new design;

FIG. 2 is a front elevational view thereof;

FIG. 3 is a side elevational view thereof, the opposing side elevational view being identical;

FIG. 4 is a rear elevational view thereof;

FIG. 5 is a top plan view thereof; and

FIG. 6 is a bottom view thereof;

FIG. 7 is a front perspective view of a second embodiment showing a white opaque bottle;

FIG. 8 is a front elevational view thereof;

FIG. 9 is a side elevational view thereof, the opposing side elevational view being identical;

FIG. 10 is a rear elevational view thereof;

FIG. 11 is a top plan view thereof; and

FIG. 12 is a bottom view thereof;

FIG. 13 is a front perspective view of a third embodiment showing a blue translucent bottle, the color being represented by the solid horizontal lines;

FIG. 14 is a front elevational view thereof;

FIG. 15 is a side elevational view thereof, the opposing side elevational view being identical;

FIG. 16 is a rear elevational view thereof; and

FIG. 17 is a top plan view thereof; and

FIG. 18 is a bottom view thereof;

FIG. 19 is a front perspective view of a fourth embodiment showing a colorless transparent bottle;

FIG. 20 is a front elevational view thereof;

FIG. 21 is a side elevational view thereof, the opposing side elevational view being identical;

FIG. 22 is a rear elevational view thereof; and

FIG. 23 is a top plan view thereof; and,

FIG. 24 is a bottom view thereof.

The broken lines shown in the drawings are for illustrative purposes only and form no part of the claimed design.
